(57) CLAIM

I claim, the ornamental design for the personal memorabilia carrier, as shown and described.

DESCRIPTION

FIG. 1 is a front elevational view of the personal memorabilia carrier showing my new design;

FIG. 2 is a rear elevational view of the personal memorabilia carrier thereof;

FIG. 3 is a top plan view of the personal memorabilia carrier thereof;

FIG. 4 is a bottom plan view of the personal memorabilia carrier thereof; and,

FIG. 5 is a perspective view of the personal memorabilia carrier thereof.

It being understood that the broken lines in FIG. 5 are for illustrative purposes only and form no part of the claimed design.
